(57) **CLAIM**

We claim an ornamental design for an audio control device, as shown and described.

DESCRIPTION

FIG. 1 is a first perspective view of an audio control device showing the claimed design;

FIG. 2 is a second perspective view of FIG. 1;

FIG. 3 is a third perspective view of FIG. 1;

FIG. 4 is a front elevational view of FIG. 1;

FIG. 5 is a rear elevational view of FIG. 1;

FIG. 6 is a left side elevational view of FIG. 1;

FIG. 7 is a right side elevational view of FIG. 1;

FIG. 8 is a top plan view of FIG. 1;

FIG. 9 is a bottom plan view of FIG. 1; and,

FIG. 10 is an enlarged view as indicated in FIG. 2.

The dashed broken lines in the figures represent portions of the article which form no part of the claimed design.

The dot-dash broken lines in the figures represent the boundary of an enlarged area which form no part of the claimed design.

1 Claim, 8 Drawing Sheets
